[57] **CLAIM**

The ornamental design for a shoe outsole, as shown and described.

DESCRIPTION

FIG. 1 is a bottom plan view of a shoe outsole according to my new design;

FIG. 2 is a cross section as shown in section 2-2 of FIG. 1;

FIG. 3 is a cross section as shown in section 3-3 of FIG. 1;

FIG. 4 is a cross section as shown in section 4-4 of FIG. 1;

FIG. 6 is a side elevational view of one side of a shoe outsole as shown in FIG. 1; and,
FIG. 7 is a side elevational view of the other side of the

shoe outsole as shown in FIG. 1.
The broken line showing of a shoe upper is for illustrative purposes only and forms no part of the claimed design.

FIG. 2

FIG. 4

FIG. 5

FIG. 7
